(57) **CLAIM**

The ornamental design for a ceiling fan canopy and downrod as shown and described.

DESCRIPTION

FIG. 1 is a front top perspective view of a ceiling fan canopy and downrod showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front bottom perspective view thereof; and,

FIG. 9 is a front top perspective view thereof, shown in an environment thereof.

The broken lines illustrate portions of the ceiling fan canopy and downrod and form no part of the claimed design.
